UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

TYPE-METAL MELTING-POT.

No. 857,433.

Specification of Letters Patent.

Patented June 18, 1907.

Application filed August 22, 1906. Serial No. 331,604.

To all whom it may concern:

Be it known that I, HENRY F. BECHMAN, of Battle Creek, in the county of Calhoun and State of Michigan, have invented certain new and useful Improvements in Type-Metal Melting-Pots; and I hereby declare that the following is a full, clear, and exact description thereof, reference being had to the accompanying drawings, which form part of this specification.

This invention is an improvement in type-founders melting pots such as are used in making stereotype plates, and in type-foundering, wherein a large reservoir of molten metal is maintained during the ordinary operations of the casting machine and is pumped from the pot as needed during the casting operations. Customarily these pots contain a large amount of metal and in order that the pump may operate successfully the metal must be maintained at an approximately constant level in the pot so as to keep the pump sufficiently submerged, and it sometimes happens that toward the end of the casting operations the stock of fresh metal is exhausted and the level of the metal in the pot drops below the desired point and a great deal of annoyance and sometimes loss, is caused by the delay required in obtaining a further supply of metal sufficient to enable the metal in the pot to be replenished so that the pump can operate. At the same time it is desirable at the end of the casting operation to have as little metal as possible left in the pot, so that it can be subsequently remelted with greater rapidity than if a large amount is left therein.

The object of the present invention is to enable the founder to continue the casting operations until the amount of metal in the pot is reduced far beyond what it is possible to do with the apparatus as ordinarily constructed, unless a fresh supply of metal is provided; so that, in case of emergencies, where the metal runs short near the end of the operation and there is no fresh metal on hand, the founder can—by a very simple mechanical device—cause the metal in the pot to rise to the desired level in the pump and keep it up to the necessary level until the metal is practically all exhausted.

To this end the invention resides, in short, in providing means for raising the molten

metal in the pot, so that as its quantity lessens the operator can gradually introduce 55 into the pot a displacing body, by which the molten metal will be caused to rise to a higher level therein than that at which it would naturally stand.

The invention will be fully understood 60 from the following description of the apparatus illustrated in the following drawings, which show several modifications of devices adapted to accomplish the desired end.

In the drawings—Figure 1 is a part elevation and part sectional view of a melting pot provided with my displacing device; Fig. 2 is a top plan view thereof; Fig. 3 is a sectional view of a slight modification thereof.

The metal pot 1 may be of ordinary construction, and is placed over a furnace 2, such as is commonly employed for this purpose, and is provided with a metal pump 3, of usual construction, provided with a discharge outlet 3^a by which the molten metal 75 can be delivered to the point of utilization. The construction of these parts of the apparatus is well-known and needs no particular detailed explanation.

The molten metal in the pot 1 should be 80 kept at such level, substantially as shown, that it will completely fill the pump 3, which should be practically kept submerged in the metal, so that there will be no possibility of the metal chilling in the pump. As the 85 metal is withdrawn from the pot through the pump the molten metal level would descend, but its level is maintained customarily by adding, either by hand or automatically, fresh solder or type metal to be melted there- 90 in. If, however, it should happen that the supply of fresh metal should become exhausted before the casting operations are completed, with the apparatus as heretofore used it would be necessary to suspend the 95 casting operations until fresh metal could be obtained,—because after the metal drops below a certain point in the pump the apparatus becomes ineffective. At such times my invention becomes useful, and it consists 100 in the employment of a displacer used to raise and maintain the molten metal at the proper level in the pump when the pot is nearly exhausted, and no fresh metal is added.

As shown in Figs. 1 and 2, the displacer 105 comprises a body 4, which is adapted to be

gradually lowered into the pot 1, and of course as it is lowered therein it displaces the metal and will cause the level of the latter to rise in the pot and around the pump. The 5 displacer 4 may be solid or hollow. I prefer to make it hollow and then weight it, by putting dross or any other matter therein, until the weight of the body 4 is about equal to that of the mass of molten metal which it 10 would displace if substantially submerged therein.

As shown in Figs. 1 and 2, the displacer 4 is provided with an arm 4^a which is fulcrumed at 4^b on the edge of the body, so that 15 by oscillating the outer end of said arm the displacer can be raised or lowered in the pot. The outer end of the arm 4^a is engaged by a screw 5, which passes through a nut 4^c swiveled on arm 4^a and pivotally engaged with a 20 retainer 2^a on the casing on which the pot is supported. By rotating the screw 5 it will be obvious that the arm 4^a can be moved so as to raise or lower the displacer 4 at will. Normally the displacer 4 will be raised above 25 the level of the fluid, but when the fresh supply of metal is exhausted and it is still desired to continue casting operations, the founder turns screw 5 so as to lower the displacer 4 into the molten metal and raise the 30 latter to the proper height, thus he can continue the casting operations until the displacer is completely lowered, by which time practically all the metal in the pot will have been used; which procedure would have been 35 absolutely impossible in the ordinary constructions of melting pots and pumps.

As shown in Fig. 3, the displacer 6 is attached to the lower end of a screw 6^a, which

passes through a threaded boss 6^b supported on a bracket or arch 6^c attached to the pot 1 40 or frame 2, which is otherwise constructed as in Fig. 2. By rotating screw 6^a by its hand wheel 6^d, the displacer 6 can be raised or lowered into the pot, as desired, with the same effect as in the construction shown in 45 Fig. 1.

Having described my invention what I claim as new and desire to secure by Letters Patent is:

1. In a type metal melting pot, the combination of the pot, a metal pump, a body adapted to be lowered into the pot to displace the metal therein and raise its level in the pot and pump, a rotatable screw, and connections between said screw and the body 55 and the pot, whereby said body may be positively moved in or out of the pot and secured in any adjusted position, substantially as set forth.

2. In combination with a furnace, a melting pot therein, a pump therein for forcing metal therefrom, a displacer, a hinged lever supporting said displacer, and a rotatable screw pivotally connected to the outer end of said lever and to a fixed point, and adapted 65 to regulate the position of the displacer in the pot and maintain the molten metal at the desired level, substantially as described.

In testimony that I claim the foregoing as my own, I affix my signature in presence of 70 two witnesses.

HENRY F. BECHMAN.

In presence of—

F. W. DUNNING,
Wm. JAMES MOLYNEUX.
